UNITED STATES PATENT OFFICE

RICHARD P. ENDERLIN, OF CIRCLEVILLE, OHIO, ASSIGNOR TO FORALINE PRODUCTS INC., OF CIRCLEVILLE, OHIO, A CORPORATION OF OHIO

DESIGN FOR A JAR OR SIMILAR ARTICLE

Application filed May 19, 1931. Serial No. 39,907. Term of patent 7 years.

To all whom it may concern:

Be it known that I, RICHARD P. ENDERLIN, a citizen of the United States, and a resident of Circleville, county of Pickaway, and State of Ohio, have invented a new, original, and ornamental Design for a Jar or Similar Article, of which the following is a specification, reference being had to the accompanying drawings, forming a part thereof.

I claim:

The ornamental design for a jar or similar article as shown.

Signed by me, this 28th day of April, 1931.

RICHARD P. ENDERLIN.
